UNITED STATES PATENT OFFICE.

EMIL LARIUS, OF HIBRIDGE, NEW YORK.

ORTHOPEDIC SHOE AND BOOT.

Application filed October 23, 1922. Serial No. 596,373.

This invention relates to orthopedic shoes and boots.

More particularly the invention relates to shoe construction and the method of constructing the same.

Some of the objects of the present invention are: to produce a shoe or the like constructed in a comparatively scientific manner so that conditions of foot malformation may be corrected and at the same time give comfort to the individual; to produce a shoe or the like which embodies an insole having a main arch supporting portion; to provide a shoe with an insole of the character mentioned with individual parts to provide the required prominence or prominences at a proper point or points to overcome the disadvantages of natural foot imperfections; and with these and other objects in view, the invention resides in the particular construction, and the art of attaining the same hereinafter fully described.

In the drawing which forms a part of this specification:

25 Figure 1 is a perspective view of the insole per se.

Figure 2 is a perspective view of one of the filler pieces.

30 Figure 3 is a perspective view of another filler piece.

Figure 4 is a longitudinal sectional view of the insole.

35 Figures 5, 6 and 7 are transverse sectional views showing several views of the present invention as applied to a shoe and these views are taken through the toe, instep and heel portion respectively of the shoe.

The invention in the present case in part, is predicated upon the use of an insole such 40 as the one shown in Figure 1 of the drawing.

This insole 10 is constructed so that it has an arch support 11 and an arch 12 extending from the arch support to the toe portion thereof, the latter constituting the ball portion 45 of the insole. The present insole differs however from the ordinary insole in that at the arch support 11 thereof the present insole is provided with a lateral upwardly extending supporting portion 13. It will be manifest 50 that the portion 13 is disposed to give support to the arch of the foot to the best advantage. In order that the foot of an individual may have the arch supported in a proper manner the insole 10 is provided at 55 the ball thereof with a concavo-convex portion to provide a cavity which arches the in-

sole at the ball thereof transversely as well as longitudinally. The concavity at the upper side of the ball portion of the insole 10 accommodates the disproportioned ball of an individual's foot and allows the same to set 60 relatively low while the arch is supported in its relatively high curved condition. A filler piece 14 as shown in Figure 2 of the drawing is employed at the ball portion of the insole 10 and a filler portion 15 as shown in Figure 3 is employed at the heel portion of the insole. These parts 14 and 15 are applied to the insole, and make the latter of greater thickness at 65 one side than at the opposite side at the particular point of application of the parts 14 and 15. The greater thicknesses are on the inner side of the ball portion 12 of the insole. 70

In order that use may be made of the parts hereinbefore described, it is necessary to follow certain steps for the construction of the shoe or the like in accordance with the present invention. The steps are as follows:

The insole 10 is applied to a last having a prominence at the ball thereof with a filler 80 piece such as the piece 14 at the ball portion of the insole between the latter and the bottom face of the last, with a filler piece such as the piece 15 at one portion of the insole between the latter and the bottom face of the 85 last, with a padding 16 and lining 17 covering the parts 14 and 15, then applying the upper, securing the upper to the insole and completing the manufacture of the sole in the ordinary way. The effect of this procedure results in the production of a shoe, which at the portion thereof that accommodates the ball of the foot, is provided with a cavity 18 90 and an angularly disposed inner surface which is higher at one side than the opposite 95 side; and one which at the portion thereof which accommodates the heel portion of a foot will have an angularly disposed inner surface which is higher at one side than the opposite side.

100 From the foregoing it will be manifest that in order to carry out the present invention it is necessary to make use of the several parts thereof in a particular manner and that it is further necessary to employ the several 105 parts by constructing the shoe in accordance with certain prescribed steps. It will also be manifest that the orthopedic arrangement is such as to meet the common condition but where unusual conditions are to be made, 110 satisfactorily made boots shaped to the foot are employed.

It is to be understood that while the main arch in each case will have the supporting portion 13 in some cases the filler portion 14 will not be used while in other cases the filler piece 15 will not be used. In other words both portions 14 and 15 may be used in conjunction with the portion 13 or either one of the parts 14 or 15 alone may be used in connection with the portion 13.

10. What is claimed is:

In an article of footwear, an insole including an arch portion and a ball portion, said ball portion being concavo-convex longitudi-

nally and transversely to provide a concavity therein, a laterally upwardly extending portion formed at one edge of the arch portion, and separate elongated wedge shaped filler pieces adapted to cooperate with the laterally upwardly extending portion and the remaining portion of the insole at the inner side thereof adjacent to the heel and toe portions respectively. 15 20

In testimony whereof I have affixed my signature.

EMIL LARIUS.
